UNITED STATES PATENT OFFICE.

JESSE Z. CASADY, OF DEAN, IOWA.

WIRE CLOTHESPIN.

Application filed February 15, 1923. Serial No. 619,155.

To all whom it may concern:

Be it known that I, JESSE Z. CASADY, a citizen of the United States, residing at Dean, in the county of Appanoose, State of Iowa, have invented a new and useful Wire Clothespin; and I do hereby declare the following to be a full, clear, and exact description of the invention, such as will enable others skilled in the art to which it applies to make and use the same.

This invention relates to clothes pins, and has for its object to provide a device of this character comprising a U-shaped jaw, an arm forming a second jaw, centrally disposed within the U-shaped jaw and a line engaging hook, all of the parts being formed from a single piece of spring wire.

A further object is to provide adjacent the upper end of the centrally disposed arm a plurality of convolutions, or bends, for increasing the range of spring action of said arm, thereby allowing a wide range of movement of the arm for clamping thick material, such for instance as a blanket.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a perspective view of the clothes line clamp.

Figure 2 is a side elevation.

Figure 3 is a front view.

Referring to the drawing, the numeral 1 designates a U-shaped clamping jaw, the lower end 2 of which preferably curves backwardly, thereby forming a transversely disposed portion 3, with which portion the eye 5 of the centrally disposed spring arm 6 cooperates for clamping and holding its garment with the garment slightly forced through the jaw 1, between the arms 7 and 8. The arm 8 extends upwardly and is bent inwardly at 9, thereby forming a horizontally disposed inwardly extending portion

10. Portion 10 is bent rearwardly substantially centrally of the device, thereby forming a rearwardly extending horizontally disposed portion 11, which forms a bearing for the loop 12 carried by the arm 6. The portion 11 at its rear end terminates in an upwardly and forwardly extending loop 13 adapted to hook over a conventional form of clothes line. The upper end of the arm 6 after being bent to form the loop 12 is bent to form the downwardly extending loop 14, which loop is preferably in the same plane as the arms 7 and 8, and forms means for allowing a maximum range of flexibility to the arm 6 without bending or fracturing the same. It will be seen that the clamp is formed from a single piece of wire and provided with means whereby maximum flexing of the clamping arm in relation to the jaw 1 allows a relatively thick piece of material or article to be clamped and held.

From the above it will be seen that a clothes clamp is provided, which is formed from a single piece of wire, may be cheaply made, and one wherein an article of clothing may be supported on a clothes line even if the article is relatively thick.

The invention having been set forth what is claimed as new and useful is:—

A clothes line clamp, said clamp comprising a U-shaped jaw having spaced diverging arms, one of said arms having its upper end terminating in an inwardly rearwardly and upwardly extending arm, the upper end of the other arm of the U-shaped jaw terminating in an S shaped loop in the same plane as the arm, the end of said S shaped loop extending over the rearwardly extending portion carried by the other arm and terminating in a downwardly extending clamping arm.

In testimony whereof I have signed my name to this specification in the presence of two subscribing witnesses.

JESSE Z. CASADY.

Witnesses:

E. E. EWING,
JOE WALTERS.
